DRAPERY MOUNTING RING

Bernard Yellin, Chicago, Ill., assignor to Bernard Edward Co., Chicago, Ill., a corporation of Illinois

Application January 5, 1952, Serial No. 17,948

Term of patent 7 years

(Cl. D21—1)

To all whom it may concern:

Be it known that I, Bernard Yellin, a citizen of the United States and a resident of the city of Chicago, county of Cook, State of Illinois, have invented a new, original, and ornamental Design for a Drapery Mounting Ring, of which the following is a specification, reference being had to the accompanying drawing forming a part thereof in which:

Fig. 1 is a front view of a drapery mounting ring, showing my new design;

Fig. 2 is an edge view thereof, looking from the right of Fig. 1;

Fig. 3 is another edge view thereof, looking from below Fig. 1;

Fig. 4 is a cross-sectional view thereof, taken substantially on line 4—4 of Fig. 1; and

Fig. 5 is a cross-sectional view thereof, taken substantially on line 5—5 of Fig. 1.

The dotted line showing of a hanger is for illustrative purposes only.

The figures are shaded to indicate color contrast.

I claim:

The ornamental design for a drapery mounting ring, substantially as shown.

BERNARD YELLIN.
